(57) **CLAIM**

The ornamental design for a bowhunters' anchor point collar as shown and described.

DESCRIPTION

FIG. 1 is a top perspective view of the bowhunters' anchor point collar showing my new design;

FIG. 2 is a right side view thereof;

FIG. 3 is a front view thereof;

FIG. 4 is a left side view thereof; and,

FIG. 5 is a back view thereof.

The dotted lines shown in the drawings do not make up any part of the claimed design.
